AUTOMATIC STOP MECHANISM FOR ADDRESSING MACHINES

Filed Oct. 25, 1920 2 Sheets-Sheet 2

UNITED STATES PATENT OFFICE.

CLIFTON CHISHOLM, OF CLEVELAND, OHIO, ASSIGNEE TO AMERICAN MULTIGRAPH COMPANY, OF CLEVELAND, OHIO, A CORPORATION OF OHIO.

AUTOMATIC STOP MECHANISM FOR ADDRESSING MACHINES.

Application filed October 25, 1920. Serial No. 419,222.

To all whom it may concern:

Be it known that I, CLIFTON CHISHOLM, a citizen of the United States, residing at Cleveland, in the county of Cuyahoga and 5 State of Ohio, have invented a certain new and useful Improvement in Automatic Stop Mechanism for Addressing Machines, of which the following is a full, clear, and exact 10 description, reference being had to the accompanying drawings.

This invention relates to mechanism adapted to form a part of an addressing machine and operate to stop the operation upon the arising of some contingency, for instance, the 15 failure of the paper to properly feed or the magazine of address plates becoming empty.

One of the objects of the invention is to make such mechanism simple and at the same time efficient. Thus I have designed the 20 paper feeding parts with such lightness and ease of operation that they are very efficient and readily operate for the thinnest paper used as well as for the heavier grades.

Another object is to enable practically the 25 same mechanism to throw out a controlling clutch either when the paper fails to feed or the magazine becomes empty.

The invention is illustrated in an approved 30 form in the drawings hereof, and is herein- after more fully explained and its essential novel features summarized in the claims.

In the drawings Fig. 1 is a sectional side elevation of the machine; Fig. 2 is a rear elevation of a portion of the machine; Fig. 35 3 is a continuation toward the right of Fig. 2, part of this view being in section; Figs. 4 and 5 are details illustrating the position of one of the paper engaging rolls which controls the clutch, first where the paper is 40 absent, and second where the paper is present.

Referring by numerals to the parts shown in the drawings, 10 indicates the bed of the machine, and 11 one of a pair of suitable 45 frame standards rising therefrom. In these standards are mounted a shaft 12 for the paper feeding drum 13 and a shaft 14 on which the platen 15 is journaled. 20 indicates a vertical magazine for address plates, a number of which are shown at 21. These

plates descend by gravity, and the lowermost one is engaged and fed to the right (Fig. 1) by conveyer chains 24 running over sprockets 25 on a shaft 26 and over other sprockets—not shown—on the shaft 14 which 55 is suitably geared with the shaft 12. These chains have lugs 29 adapted to engage the plates and feed them to the impression members. The chain may be kept taut by adjusting the position of the bearing 28 of the 60 shaft 26. 30 and 31 indicate suitable inking rollers adapted to ink the characters on the address plates as they pass between the roller 31 and supporting roller 32.

The mechanism above described is shown 65 incidentally to illustrate the operation of the automatic stop mechanism which forms the subject matter of this application. The particular paper feed drum shown is described more fully and claimed in my co-pending re- 70 issue application No. 356,279, filed Feb. 4, 1920, which has matured into Reissue Patent No. 15,419 dated July 25, 1922. As here shown it comprises, beside the body 13, a pair of segmental yielding platen members 40, 75 mounted on the body, and a pair of rings 41 at the end of the body and having their outer periphery flush with the periphery of the segmental members. Co-operating with these rings are rollers 50 and 51 which have 80 their axes parallel with the shaft 12 and project thru openings in a stationary guard plate 52.

The paper is fed by mechanism—not 85 shown—but which may be in accordance with my Patent No. 1,285,623, issued November 26, 1918, from a position above the paper feeding drum downwardly toward the left in Fig. 1, between the drum and the shield 52. The paper when passing between the 90 shield and drum is held against the drum by the rollers 50 and 51 acting successively on the paper until it comes above the impression platen. At this time one of the segmental members 40 is above the platen 15 and 95 one of the plates is in a similar position, so that the plate and paper are fed together toward the right in Fig. 1 between the yielding pressure platen 15 and one of the yielding segmental platens 40.

To cause the operation of the paper feed and conveyer to stop, in case of failure of either the paper or plates, I drive the shaft 12 by means of a clutch which is thrown out 5 by the mechanism about to be described. Fig. 2 shows at 60 a driving pulley loose on the shaft 12, and at 61 a shiftable clutch splined to the shaft and adapted to couple the pulley with it, or leave it disconnected therefrom. 10 62 indicates a suitable shipper lever for shifting this splined clutch collar. This shipper lever is preferably equipped with a handle 64 for manual operation whenever desired; for the automatic operation it carries a blade 15 65 extending into a peripheral notch 71 in a longitudinally shiftable bar 70, as shown in Fig. 2. This figure shows a spring 73 tending to force this bar in the direction to disengage the clutch. Such movement is normally restrained, but may be allowed by actuation of the paper feeler mechanism to be described.

Pivotedly mounted on a stationary frame rod 75 are a pair of arms 76 and 76^a which 25 are bent as shown in Fig. 1 and carry at their ends rollers 77 adapted to ride on the rings 41. In these rings are formed segmental grooves 45 which in the rotation of the drum come opposite the rollers 77. 30 Now, if paper is present bridging the grooves 45, the rollers will be thereby held out of the grooves in the same position they occupy when other portions of the drum are opposite them. Fig. 5 indicates at A a 35 sheet of paper, or an envelope, on the drum bridging the groove 45 and shows how this maintains the roller 77 in its normal position.

If there is a failure of the paper to properly feed, then when the uncovered groove 45 comes opposite the roller 77, the roller will at once drop by gravity into the groove 45, as shown in Fig. 4. Now, when the rear end 45^a of the groove reaches the roller it 40 forces it outwardly with somewhat of a blow. This snaps the roller and its arm upwardly, so that the arm strikes against a light sheet metal stirrup 80 and raises it. This stirrup, as shown in Fig. 2, is pivotally 45 mounted on the rod 75 and has a projection 82 standing against the side of a collar 79 on the longitudinally movable rod 70. The blow of the arm 76 raises this stirrup sufficiently to clear the collar 79, whereupon the 50 spring 73 forces the rod 70 toward the right (Fig. 2) and thus operates the shipper lever 62 to disengage the clutch.

By reason of the blow operation described 60 the paper feeling arms may be light enough to be supported in their inactive position by the thinnest paper used bridging the recesses 45, at the same time the spring 73 may be strong enough to effectively shift the clutch lever and normally hold the parts in 65 position against accidental displacement.

It is desirable that the mechanism be arranged to feed two envelopes for each rotation of the drum 13, or one envelope, or a sheet of paper, when the same are of larger size. To accomplish this I provide the two 70 platens 40, and I arrange them so that one or both of them may be presented to the successive address plates; that is to say, I provide change speed gearing adapted to be shifted to cause the drum 13 to make either 75 one rotation or a half rotation for each address plate fed. Such a system is shown, described and claimed in my prior application No. 371,722, filed April 6, 1920. In the present invention I provide two paper feeling arms 76 and 76^a, and I arrange one of these to have a possible operation only once for each rotation of the drum 13, while the other may possibly operate twice for each rotation. This arrangement and the mechanism for 80 rendering only one arm or the other active, in accordance with the condition of the change speed gearing, will now be described.

As shown in Fig. 3, the shaft 12 which carries the printing drum also serves to 90 drive the conveyer chains thru variable gearing. In Fig. 3, 90 and 91 indicate meshing gears of the same size on the shafts 12 and 14. 92 and 93 indicate meshing gears on these shafts, the latter gear having twice the 95 diameter of the former. The gears 91 and 93 are tight on the shaft 14, which operates the conveyer chains, the impression platen 15 being loose on the shaft.

The driving gears 90 and 92 are both 100 loose on the shaft 12, and either of them may be clutched to this shaft by a sliding key 95 which occupies a keyway in the shaft 12 and has a radially projecting end adapted to engage a notch 96 in the hub of the gear 90, or a notch 97, in the hub 92. As shown in Fig. 3 when the key projection occupies an intermediate position both gears are out of action.

To shift the key 95, I form a projection at 110 its outer end, which occupies a peripheral groove in a bushing 100 carried by a shiftable bracket 101. This bracket is mounted on a sliding rod 102. On this rod are a pair of collars 103 and 104 having inclined edges, 115 as shown in Fig. 2. These collars are adapted to clear or engage their respective arms 76, 76^a, and are so positioned that when one collar is engaging its arm the other collar is free therefrom, as shown in Fig. 2.

If the bracket 101 be in the position shown in Fig. 3, the gear 92 will be locked to the shaft and the collar 103 will be brought beneath the arm 76, the collar 104 clearing the arm 76^a. The arm 76 and its roller 77 are thus held inactive, but the arm 76^a and its roller are active. The drum ring which co-operates with the roller of this arm has one arcuate groove 45, so that but one test 120 will be made for the presence or absence of 125 130

paper for each rotation of the drum 13. When the gear 92 is active, as now supposed, the conveyer chain shaft 14 will make a half rotation for each rotation of the drum 13.

5 Each half rotation of the shaft 14 brings a fresh plate to the printing position, since the conveyer chain lugs 29 are spaced a distance corresponding to half the periphery of the sprockets on the shaft 14 which carry the 10 chains. Accordingly each rotation of the shaft 12 feeds either one large envelope or a sheet of paper, and one test is made for its presence or absence.

If the bracket 101 be drawn toward the 15 right from the position shown in Fig. 3, the gear 90 will be coupled to the shaft 12 and at the same time the collar 104 will raise the arm 76^a into inactive position and the arm 76 will become active being freed by the removal of the collar 103. With this gear connection there will be one rotation of the shaft 14 for each rotation of the shaft 12. As the plate feeding lugs 29 on the conveyer 20 chains are spaced a distance corresponding to half the periphery of the sprockets on the shaft 14, it follows that each rotation of this shaft will bring two plates to printing position, and this would require two pieces of paper, or envelope, to be printed. This is 25 the coupling which I employ for ordinary envelopes, one being printed when one of the segmental platens 40 is active and the other when the other platen 40 is active. The arm 76 which is active under these circumstances has its roller 77 riding on a ring 41 which carries two arcuate grooves 45, as shown in Fig. 1, so that in this case the two tests are made for each rotation of the drum.

It will be seen from the above description 40 that my stop mechanism is automatically positioned in correspondence with the change in the gearing when the machine is changed from ordinary envelopes to large size envelopes or paper, or vice versa, the 45 simple shoving in or pulling out of the bracket 101 accomplishing both the adjustment of the gearing and of the throw-out mechanism in a very simple manner.

To enable the same throw-out mechanism 50 to stop the operation when the supply magazine becomes empty, I provide an arm 110 pivoted to the side of the magazine at 111 and adapted to lie against the forward edge of the plates. To the upper end of this arm 55 is pivoted a bar 112 which rests at its rear end on the rod 102 and intermediately extends beneath the stirrup 80, having a recess 114 normally occupied by the cross member of the stirrup. Ordinarily the bar 60 112 is idle, but whenever the magazine becomes empty the arm 110 becomes thereby freed from restraint, and a spring 116 swings the upper end of this arm forwardly 65 to cause the inclined shoulder on the bar 112 at the rear of its notch 114 to cam the stir-

rup upwardly. This releases the rod 70 which is thereupon moved by its spring to swing the shipper lever to disengage the clutch, in the same manner as heretofore described.

Having thus described my invention, I claim:

1. In an addressing machine, the combination, with a rotary paper support having a recess, a member adapted to move into the recess when the paper is absent, and means whereby the return of such member from the recess will effect a stoppage in the operation of the machine.

2. In a machine of the character described, the combination, of a rotary member about which paper may be fed, said member having a groove, a roller adapted to stand opposite the groove and bear against paper bridging the groove, means carrying the roller and allowing it to move into the groove when paper is absent, and means operated by the return of said roller for stopping the operation.

3. In a machine of the character described, the combination, of a rotary drum with which paper may travel, said drum having an arcuate groove, a member adapted to bear on the paper opposite said groove, and mechanism operated by the entry of the said member into the groove and its return therefrom for stopping the rotation of the drum.

4. The combination, of a rotary drum, means for guiding paper on the periphery thereof, said drum having a recess adapted to be bridged by the paper, an arm, a roller carried thereby and adapted to bear on the paper where it bridges the recess, a clutch, and mechanism operated by said arm for throwing the clutch.

5. The combination, of a rotary drum, means for guiding paper about the periphery thereof to be fed with the drum, said drum having an arcuate recess, an arm, a roller carried by the arm and adapted to enter the recess when the paper is absent, but be held out of the recess when the paper is present on the drum, means for stopping the operation of the machine and mechanism for operating said means, which mechanism is operated by the return movement of said arm after the roller has entered the recess.

6. The combination, of a rotary drum adapted to have paper travel with it about its periphery, a recess in such periphery, a movable member adapted to bear against the paper in a position which in some portion of the rotation is opposite the recess, a clutch, mechanism for disengaging the same, and means whereby the impact of said member, as it comes out of the recess, throws said disengaging mechanism.

7. The combination, of a rotary drum adapted to have paper travel with it about

its periphery, a recess in such periphery, a movable member adapted to bear against the paper in a position which in some portion of the rotation is opposite the recess, a clutch, a spring pressed mechanism tending to move the clutch into disengaged position, means for normally restraining the spring action of such mechanism, and means whereby the impact of said member when it leaves the recess may move the restraining member to idle position.

8. In a machine of the character described, the combination, with means for guiding and feeding paper, of a feeler bearing on the paper and adapted to be opposite a recess on the other side of the paper, a clutch, a spring device tending to release the clutch, and restraining means adapted to hold the clutch engaged, and means whereby the impact of said feeler as it leaves the recess will move said restraining means to idle position.

9. The combination, with an impression platen, of a drum coacting therewith and having a plurality of impression surfaces, change speed gearing to cause paper to be fed to one or more of said surfaces, throw-out device to stop the machine when the paper fails, and means for concurrently changing the gearing and correspondingly adjusting the throwout device.

10. In a machine of the character described, the combination, of a rotary drum, means for feeding, as desired, either one or two articles for each rotation of the drum, a throwout device having two feelers, one operative once a rotation, and the other operative twice a rotation, and means for rendering one or the other feelers active according to whether the mechanism is feeding one or two articles for each rotation.

11. In a machine of the character described, the combination, of a platen, a rotary paper feeding drum coacting therewith, and having two impression surfaces, conveyer means for feeding plates between the drum and platen, changeable gearing between the drum and the conveyer means to enable either one or two plates to coact with the drum, a clutch for stopping the operation, a throwout device for the clutch having two feelers coacting with the drum, one arranged to operate once a rotation and the other twice a rotation, and a device for simultaneously shifting the gearing and rendering the corresponding feeler active and the other inactive.

12. In a device of the character described, the combination, of a bottom feed address plate magazine, a conveyer, a clutch for driving the conveyer, mechanism for moving the clutch to disengaged position, and a movable member adapted to bear against a plate in the magazine and be thereby restrained from operation, and mechanism op-

erated by said movable member when the plates are absent for releasing the clutch disengaging means.

13. In an addressing machine, the combination, of a bottom feed supply magazine, a conveyer, an arm bearing against a plate in the magazine, a clutch for operating the conveyer, mechanism for releasing the clutch, and means operated by the movement of said arm when the plate is absent for actuating the clutch releasing means.

14. In an addressing machine, the combination, of a supply magazine for address plates, a lever adapted to engage said plates and be restrained thereby, a clutch, a spring pressed member tending to uncouple the clutch, but normally restrained, and means connected with said lever for removing the restraint when the lever moves consequent upon the absence of the plates in the magazine.

15. In an addressing machine, the combination, of a magazine, a conveyer adapted to receive plates therefrom, a clutch for moving the conveyer, a shipper lever for the clutch, a spring pressed member for tending to move the shipper lever to open the clutch, a device for restraining the movement of said member, a lever adjacent to the magazine and held idle by the presence of plates therein, but adapted to be moved when the plates are absent, and an operative connection between said lever and the means which restrains said member.

16. In an addressing machine, the combination, of a supply magazine, a conveyer, a pair of impression members to which the conveyer may carry plates from the magazine, one of said impression members being adapted to act as a paper feeding roller, mechanism operated by the absence of plates in the magazine, another mechanism operated by the absence of paper on the roller, and a single throwout device operated by either of said mechanisms.

17. In an addressing machine, the combination, of a supply magazine, a conveyer, a pair of impression members to which the conveyer may carry plates from the magazine, one of said impression members being adapted to act as a paper feeding roller, mechanism operated by the absence of paper on the roller, a clutch adapted to control the movement of both the paper roller and the conveyer, a spring pressed member tending to release said clutch, and means for restraining said member, said means being movable to idle position by either of the mechanisms mentioned.

18. In an addressing machine, the combination, of a supply magazine, a conveyer, a pair of impression rollers between which the conveyer may convey plates from the magazine, means whereby one of said rollers acts as a paper feed drum, a recess in such

drum adapted to be bridged by the paper when present, a feeler co-operating with said recess and adapted to be held out of it by the paper, an arm tending to move 5 into the magazine and adapted to be held out of it by the presence of plates therein, a clutch for controlling the movement of

both the conveyer and the paper feed drum, and means initiated by either the paper feeler or the plate lever for opening the 10 clutch.

In testimony whereof, I hereunto affix my signature.

CLIFTON CHISHOLM.
